CLAIM

The ornamental design for a protective cover for an integrated antenna/downconverter, as shown.

DESCRIPTION

FIG. 1 is a front view in elevation of a protective cover for an integrated antenna/downconverter showing my design;

FIG. 2 is a rear view in elevation of the protective cover for an integrated antenna/downconverter of FIG. 1;

FIG. 3 is a side view in elevation of the protective cover for an integrated antenna/downconverter of FIG. 1 as seen from the left-hand side of FIG. 1, the other side view being a mirror image of this figure;

FIG. 4 is a top view of the protective cover for an integrated antenna/downconverter of FIG. 1; and,

FIG. 5 is a bottom view of the protective cover for an integrated antenna/downconverter of FIG. 1.
